UNITED STATES PATENT OFFICE.

ARTHUR W. PETERSON, OF WORCESTER, MASSACHUSETTS.

ADJUSTABLE SUPPORT FOR DRILLS AND THE LIKE.

1,279,153.

Specification of Letters Patent. Patented Sept. 17, 1918.

Application filed May 16, 1917. Serial No. 169,077.

To all whom it may concern:

Be it known that I, ARTHUR W. PETERSON, a citizen of the United States, residing at Worcester, in the county of Worcester and 5 State of Massachusetts, have invented a new and useful Adjustable Support for Drills and the like, of which the following is a specification.

This invention relates to an adjustable support 10 particularly designed for use with ratchet drills and other similar tools.

To render such tools effective it is essential that a rigid support or brace be provided against which the thrust of the tool may be 15 received. These tools are commonly used to drill holes and perform other operations on structural steel members of all sizes and shapes as well as on pipes and tubes of different diameters, and the provision of a 20 suitable support under such conditions is often a troublesome problem. The difficulty is often increased by the limited space and the awkward positions in which the operations must be performed.

25 It is the object of my invention to provide an improved adjustable support for such purposes which is adaptable for use under widely differing conditions.

An important feature of my invention relates 30 to the devices by which the support may be attached to the different structures on which it is used.

Other features of my invention relate to arrangements and combinations of parts 35 hereinafter described and more particularly pointed out in the appended claims.

A preferred form of my invention is shown in the drawings, in which—

Figure 1 is a side elevation of my invention 40 as applied to an I-beam;

Fig. 2 shows the invention applied to an I-beam having its upper edge embedded in concrete so that no part of the support can overlie the beam;

45 Fig. 3 shows the invention in use where a hole is to be drilled through the foot of the I-beam;

Fig. 4 shows the support applied to a large pipe or tube;

50 Fig. 5 is a bottom plan view of the bar underlying the I-beam in Fig. 2, and

Fig. 6 is an end elevation of the rocking lever which is pivotally mounted on said bar.

Referring particularly to Fig. 1 in which

I have shown my adjustable support applied to an I-beam A, it will be seen that the support comprises a bar 10, a rod 11, a brace arm 12, a rocking lever 13, a toothed rod 14, an adjustable engaging device 15, and a clamp 16.

The construction of the bar 10 is best shown in Fig. 5. A series of perforations extend transversely through the bar, and the bar is also provided with a series of slots 21, extending at right angle to the perforations 20. At one end the bar is divided or split as far as the first slot 21. This split portion includes a bearing 22, for the rod 11, and clamping bolts 23 are provided for drawing the two parts of the bar together on each 70 side of the bearing. The rod 11 is longitudinally adjustable in this bearing, and may thus be held rigidly in any desired position.

The lever 13 is pivoted to the bar 10 by a stud 25 extending through a selected perforation 20 in said bar. Inwardly projecting ears 26 (Fig. 6) prevent accidental displacement of the lever from the bar, when the stud is removed. A clamping screw 27 is threaded into one end of the lever, and engages the bar 10, thus forcing the opposite end of the lever toward the bar, and applying clamping pressure to the structure upon which the support is being used. The simplest use of the lever 13 is shown in Figs. 2 85 and 3.

The bar 10 is also provided with a hook-shaped projection 10^a at one end, which is shown in use in Fig. 3. The clamp 16 is adjustable along the rod 11 to any desired position, as shown in Figs. 1 and 2, and the brace arm 12 may also be clamped to the rod 11 in any desired longitudinal or angular position. The ends of the parts 12 and 16 are split similar to the bar 10 and are drawn together by clamping bolts to firmly grip the rod 11.

In Fig. 2 I have also shown a supplementary rod 28 adjustable upon the rod 11, and supporting the brace arm 12. In this view 100 I have also shown the rod 11 as extended upwardly into a slight recess cut in the cement floor F, this being a convenient means for supporting the upper end of the rod, when it is impossible to secure access to the 105 upper surface of the I-beam or other structure to which the support is to be applied. A ratchet tool of the usual type is indi-

cated at R, this tool forming no part of my invention, and it will be understood, that any other tool may be substituted therefor.

In Fig. 1 the support is shown clamped to the lower end or foot of an I-beam by the use of the toothed rod 14 pivoted to the lever 13 and provided with an engaging device 15 having a projecting lug 15^a yieldingly forced into engagement with the toothed rod by a spring 30. This enables me to clamp the device to the lower face of any supporting structure, regardless of the width thereof, and without the use of supplementary pieces.

In Fig. 4 I have shown the device applied to a large pipe or tube B and for this purpose I use a chain 31, one end of which is provided with a stud 32 threaded into the clamp 16 and the opposite end portion of which is secured to the rocking lever 13. The chain is thus drawn firmly about the pipe and the support is held rigidly in any desired position. The slots 21 are provided as clearance spaces for the idle part of the chain.

While I have shown only a few uses of my improved support it will be evident that there is no limit to the number of different structures to which it may be applied.

Having thus described my invention, it will be evident that changes and modifications can be made therein, by those skilled in the art without departing from the scope and spirit of my invention as set forth in the claims, and I do not wish to be otherwise limited to the details herein disclosed but what I do claim is:—

1. An adjustable support comprising a bar, a rod perpendicular thereto, means to secure said bar and rod together, a rocking lever, means to pivotally secure said lever in any one of a series of operative positions on said bar, means to rock said lever about its pivot, thereby exerting pressure substantially perpendicular to said bar and securing said support to the structure to which

it is applied, and means mounted on said rod effective to resist the thrust of a tool operating against said structure.

2. An adjustable support comprising a bar, a rod, means to secure said rod in longitudinally adjusted position in said bar, a rocking lever, means to pivotally secure said lever in any one of a series of operative positions on said bar, an engaging device adjustably connected to said lever, means to rock said lever to render said engaging device operative and means mounted on said rod effective to resist the thrust of a tool operating against the structure to which said support is applied.

3. An adjustable support comprising a bar having a series of perforations therethrough and having a split bearing near one end, a rod longitudinally adjustable in said bearing, a brace arm, means to clamp said arm in adjusted position on said rod, a lever, a stud by which said lever may be pivoted to said bar at any one of the perforations therethrough, means carried by said rod and lever effective to engage and grip the structure to which the support is applied, and means to move said lever.

4. An adjustable support comprising a bar, a rod, means to secure said rod in longitudinally adjusted position in said bar, a clamping lever, means to pivotally secure said lever in any one of a series of operative positions on said bar, a toothed rod pivotally connected to said lever, an engaging device adjustably mounted on said toothed rod and having a projection adapted to engage the teeth thereof, means to move said lever to render said engaging device operative and means mounted on said first named rod effective to resist the thrust of a tool operating against the structure to which said support is applied.

In testimony whereof I have hereunto affixed my signature.

ARTHUR W. PETERSON.
